Primary Examiner — Elizabeth Albert*(74) Attorney, Agent, or Firm* — Lerner, David, Littenberg, Krumholz & Mentlik, LLP(57) **CLAIM**

The ornamental design for a pen, as shown and described.

DESCRIPTION

FIG. 1 is a front perspective view of a pen according to my design;
FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof; and,

FIG. 6 is a bottom plan view thereof.

The broken lines illustrate unclaimed environmental structure and form no part of the claimed design.

1 Claim, 2 Drawing Sheets(56)
